(57) **CLAIM**

The ornamental design for a hand-piece for medical ablation catheter, as shown and described.

DESCRIPTION

FIG. 1 is a front view of a hand-piece for medical ablation catheter showing our new design;

FIG. 2 is a side view thereof;

FIG. 3 is a top view thereof;

FIG. 4 is a bottom view thereof;

FIG. 5 is another side view thereof;

FIG. 6 is a front, top, side, perspective view; and,

FIG. 7 is a rear view thereof.

The broken lines shown in the figures form no part of the claimed design.

1 Claim, 7 Drawing Sheets
